UNITED STATES PATENT OFFICE.

JACOB FELBEL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

967,894.

Specification of Letters Patent. Patented Aug. 23, 1910.

Application filed November 16, 1904. Serial No. 233,030.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

10 My invention relates to typewriting machines and it has for its principal object to provide an improved escapement mechanism for such machines.

15 My invention consists in certain features of construction and combinations and arrangements of parts, all as will be set forth herein and particularly pointed out in the claims.

20 In the accompanying drawings, Figure 1 is a front to rear vertical section of a type-writing machine in which my invention is embodied; Fig. 2 is a rear elevation of the escapement mechanism; Fig. 3 is a perspective view of the dog rocker, with the rear 25 dog removed; Fig. 4 is a perspective view of said rear dog; Figs. 5, 6, 7, 8 and 9 are diagrammatic top views of the escapement mechanism showing the parts in the positions they occupy at different periods in the 30 stroke of a key; Figs. 10, 11, 12 and 13 are rear views partly in section showing the parts in the positions corresponding to Figs. 6-9 respectively; Figs. 14 and 15 are a rear elevation and a side elevation, respectively, 35 of another form of my escapement mechanism; Fig. 16 is a perspective view of a dog forming part of the mechanism shown in Figs. 14 and 15; Figs. 17 and 18 are a rear elevation and a side elevation, respectively, 40 of a third form of my escapement mechanism; and Figs. 19 and 20 are a side view, partly in section, and a back view, respectively, of a form of my invention in which a straight feed rack is employed.

45 My invention is applicable to typewriting machines generally, but it is here shown as applied to the Monarch front strike typewriter. The main frame of this machine comprises a base portion 1 from which rise 50 posts 2, which support a top plate 3. Front strike type bars 4 are pivotally mounted on a segment 5 and are connected by links 6 with sub-levers 7 which are pivoted to key levers 8 having keys 9 mounted thereon.

Each of the sub-levers extends below its key 55 lever and is formed with a slot which embraces a stationary rod 10. The construction is such that when any key is depressed the type is thrown upward and backward against the front face of the platen 11. 60 Said platen is mounted in the carriage 12 which is slidably mounted on bars or rails 13 which are supported by posts 14 which rise from the top plate 3. The carriage is drawn across the machine, sliding on the 65 rails 13, by the usual spring drum 13^a, or said carriage may be so drawn across the machine by any known or suitable power device.

70 The carriage is provided with the usual rack bar 15 with which meshes a pinion 16 which is rigidly mounted on the forward end of a shaft 17 (Fig. 2), which is journaled in a housing 18, which is mounted on the top plate of the machine. At its rear 75 end the shaft 17 has a box or cap 19 rigidly secured thereon by means of set screws 20 which are threaded through the hub 21 of said cap 19, and engage the shaft 17. A toothed escapement wheel 22 is mounted on 80 the shaft 17 by the side of the cap 19. So far as my invention is concerned, the escapement wheel may be rigidly mounted on the shaft, or said escapement wheel may be loosely mounted on the shaft as usual in 85 typewriting machines and may have rigidly connected thereto the usual ratchet wheel engaged by a pawl or pawls pivoted within the cap 19. The latter construction is employed for the purpose of leaving the shaft 90 17 free to turn backward when the carriage is moved to the right without turning the escapement wheel. The dogs are mounted on a dog rocker or carrier which may consist of any to and fro moving part controlled by the keys. In the present instance the dog rocker consists of the usual rock shaft 23 having an upwardly extending arm 24 on which the dogs are mounted and a forwardly extending arm 25 having laterally extending branches or arms 26 from which depend links 27 which connect said arms with the universal bar 28 which lies beneath the key levers 8. The rock shaft 23 is pivotally mounted in lugs or ears 100 105 which project from a bracket 29 which depends from the top plate 3. The dog rocker is restored to normal position by the usual

coiled spring 30, which is connected at one end to the shaft 23 and at the other end to the bracket 29. A loose or stepping dog 31 is mounted on the dog rocker, its upper end projecting above the top of the arm 24 into position to engage the teeth of the escapement wheel. This dog is mounted in a slot 32 in the arm 24 and is pivoted to said arm by a pin 33 (Fig. 3). The stepping dog is normally engaged by a tooth of the escapement rack, which presses it into the position shown in Fig. 3 against a portion of the arm 24 which constitutes a stop for said dog. When the dog rocker is rocked forward, the stepping dog is freed from the escapement rack and is thrown back about its pivot into position to be moved into engagement with the next succeeding tooth of the rack. This motion of the stepping dog is effected by a flat spring 34 which is secured to the arm 24 by a screw 35 and the free end of which engages the dog. This stepping dog is or may be similar in construction and operation to that ordinarily used in the Remington machine. The rear dog is made part of a device 36 which preferably has the general form shown in Fig. 4. Said device has a hub 37 which is journaled on a headed and shouldered screw 38 (Fig. 2), which is threaded into a hole 39 (Fig. 3) in the rear face of the arm 24. The rear dog is thus pivoted to rock about an axis which is substantially parallel to the direction of motion of the dog rocker, and also to the axis of the escapement wheel. The construction is such that the dog moves back and forth with the dog carrier toward and from the escapement wheel and is also free to move with the escapement wheel by oscillating on the screw 38 as a pivot. The rear dog is moved in a direction contrary to that in which it is moved by the escapement wheel by means of a spring 40 which is coiled about the hub 37, and which at one end engages the pivoted device 36 and at the other end presses against a pin 41 projecting from the arm 24. The motion of the rear dog under the impulse of the spring 40 is adjustably limited by a set screw 42 which is threaded through a bracket 43 which projects rearwardly from the arm 24. The screw 42 is secured in adjusted position by a lock nut 44.

The device 36 has a forwardly extending portion 45, 46 which constitutes the holding dog, the part 45 of which is engaged by the screw 42, the part 46 of the dog being adapted to coöperate with the teeth of the escapement rack or wheel. The part 46 projects toward the front of the machine above the arm 24 and, when the rocker is rocked forward, is engaged by a tooth of the escapement rack, as shown in Fig. 6. When the rear dog 46 moves into the path of a tooth of the escapement rack and the stepping

dog moves out of engagement with said tooth, the rear dog is momentarily held against motion with the escapement rack and said rack and the carriage are thus momentarily held against motion by pressure due to the pressure of the finger on the key. This pressure may be applied in a variety of ways. In the instance illustrated in Figs. 1-13, I have provided two pressure members, one of which consists of a pin or finger 47 which has a threaded portion that is screwed into a threaded hole in a laterally extending arm 48 of the device 36 and which is provided with a lock nut 49. When the dog rocker is in its forward position the pressure pin or finger 47 engages an inclined surface which preferably consists of the surface of the cap 19 which is beveled for the purpose, as shown in the drawing, said beveled surface having the form of the frustum of a cone. The action of these parts will be best understood by reference to Figs. 5-13.

In Figs. 5-9 one of the teeth of the escapement wheel 22 is shown in section and the general position of the escapement wheel is indicated by dotted lines. A portion of the cap 19 is indicated in section so as to show the manner in which its inclined surface controls the motion of the dog. These figures of the drawing are diagrammatic, and the top of the arm 24 is conveniently represented therein by a rectangle, though this is not the precise form of said arm. Figs. 10-13 are vertical sections of the parts looking from the rear of the machine, the section being taken just inside the lateral arm 48 of the device 36. The position of said arm is indicated by dotted lines.

In Fig. 5 the parts are shown in normal position with the stepping dog in engagement with a tooth of the escapement rack.

In Figs. 6 and 10 the parts are shown in the position they occupy at the end of the down-stroke of the key, the stepping dog 31 being disengaged from the escapement rack and the rear dog being in engagement with said rack and being held against motion with said rack by the engagement of the pin 47 with the inclined surface of the cap 19. It will be perceived by an inspection of Fig. 6 that as long as the pressure on the key is maintained the pressure between the pin 47 and the cap 19 will prevent the horizontally pivoted rear dog from moving toward the left, as viewed from the back of the machine, under the impulse of the escapement wheel. The instant this pressure is relaxed the escapement wheel begins to move, pressing the rear dog toward the left about its pivot 38 and against the tension of its returning spring 40. In thus moving toward the left the rear dog is controlled or guided by the inclined surface of the cap 19 in an oblique path, as will be under-

stood by Figs. 7 and 8 which show the parts in two intermediate positions on the return movement of the rocker, and Fig. 9 which shows the parts at the instant when the rear dog is about to be freed from the escapement rack. It will be perceived that as soon as the dog rocker begins its return motion the escapement rack begins to move, impelled by the spring drum which actuates the carriage. It will be seen that it is impossible for the rear dog to let go of a tooth of the escapement rack before the stepping dog has been moved toward the back of the machine into the path of the next succeeding tooth of the rack. As soon as the rear dog moves free of the escapement rack, it is returned by the spring 40 to its normal position in engagement with the stop 42. On the forward stroke of the dog rocker the rear dog moves directly toward the escapement rack, but on the return stroke of said rocker said dog is guided in an oblique path away from said rack. The present escapement is extremely rapid, as the carriage is free to begin its motion the instant the pressure on the key is relaxed, which, as will be understood, is a great desideratum.

The form of the invention shown in Figs. 14, 15 and 16 is identical in principle with that shown in the other figures of the drawing, but differs slightly in details of construction. A tooth 50 which engages the escapement rack projects toward the front of the machine from a curved arm 51 which projects from a hub or sleeve 52 which is journaled on the screw 38 and is surrounded by the spring 40 in the same manner as the hub 37. The stop screw 42 engages the curved arm 51 to limit the motion of the parts under the impulse of the spring 40. The pressure pin 47 is threaded through a hole 53 in another curved arm 54 which projects from the hub or sleeve 52. This pin or finger engages the inclined or frusto-conical surface of the cap 19 in the same manner as in the other form. In other respects the construction is substantially identical with that above described.

In Figs. 17 and 18, I have shown a third form of my invention. A cap or wheel 19' is rigidly mounted on the end of the shaft 17, being secured by set screws 20' which are threaded through a hub 21' of said cap and engage said shaft. The cap 19' is not beveled, but is cylindrical, and has a flat rear face. A device 36', similar to the device 36, is pivoted on the screw 38, and is normally pressed against the stop screw 42 by a spring 40 in the same manner as in the first form above described. The device 36' has a forwardly projecting part 46' which is adapted to engage the teeth of the escapement wheel 22 and which constitutes the rear or holding dog. The device 36' has an arm 48' which carries a pressure pin or fin-

ger 47' which has a threaded portion which is threaded through a hole in the arm 48' and which is also provided with a lock nut 49', all of these parts being similar to the corresponding parts of the first form of the invention. The parts normally stand in the position shown in Fig. 18, with the stepping dog in engagement with the escapement wheel. When a key is depressed, the dog rocker is rocked forward, freeing the stepping dog from the escapement wheel and moving the dog 46' into engagement with said escapement wheel. At the same time, the end of the pressure pin 47' engages the flat rear face of the wheel 19', near the edge of said wheel. The pin 47' is pressed against the face of the wheel 19' by the pressure applied to the key, and as long as such pressure is maintained, the escapement wheel and carriage will be held against motion by the friction between the pressure pin and the wheel. The tendency of the parts to move under the impulse of the carriage spring is resisted by this friction in two ways. In the first place, the pin 47' acts as a brake on the wheel 19' and this alone might be sufficient to hold the parts. It is to be noted that said pin engages said wheel at a distance from the axis of said wheel greater than the radius of the pinion 16 (Fig. 1), which gives the brake a certain mechanical advantage over, or leveragé on the carriage spring. The friction of the parts resists the carriage spring in the second place by virtue of the fact that the escapement wheel can turn only by rocking the device 36' about its pivot, which would drag the pressure pin 47' across the face of the wheel 19', and this motion of said device 36' is also resisted by friction. The pin 47' acts as a brake on the wheel 19', which also, through said pin, acts as a brake on the device 36' which carries the holding dog 46'. The carriage is free to move the instant the pressure on the key is relaxed. This form of my escapement is exceedingly rapid.

It will be perceived that the braking action just described in connection with Figs. 17 and 18, is also part of the operation of the forms of the invention shown in the other figures of the drawing, and in which one of the pressure members has an inclined surface. In the form shown in Figs. 17 and 18, the carriage is momentarily held by this braking action alone; but in the other forms the parts are also held positively by the inclination of one of the pressure members as long as the pressure on the key is maintained.

In Figs. 19 and 20, I have shown a form of my invention in which a straight escapement rack 60 is employed instead of an escapement wheel. Said rack 60 is mounted on the carriage in any suitable manner.

The dog rocker is similar to that above described, and comprises an arm 24" which carries the dogs and their associated parts. Most of these parts are similar to the corresponding parts of the first form of the invention, but they are reversed in order to co-operate with rack teeth which move toward the right, as seen from the back of the machine, whereas in the first form these parts 10 co-operate with rack teeth which move toward the left. The arm 24" carries a stepping dog 31" which is pivoted on a pin 33". A device 36", corresponding to the device 36, has a hub which is journaled on a shoul- 15 dered and headed screw 38" which is threaded into the arm 24". Said device 36" has a forwardly projecting portion 46" which constitutes the holding dog, and an arm 48" in the end of which is secured the adjustable pressure pin or finger 47". The device 36" is returned to and held in normal position by a spring 40" which at one end is connected with said device and at the other end presses against a pin 41" projecting from the arm 24". Said spring normally presses said device into engagement with an adjustable stop screw 42" which is threaded through a bracket 43" of the arm 24". When a key is depressed, the arm 24" 20 is rocked forward, moving the stepping dog out of engagement with the rack and moving the dog 46" into engagement with said rack. At the same time, the pressure pin 47" is moved into engagement with a co-operating pressure member 61 having an inclined surface. In the present instance, this co-operating pressure member consists of a portion of the feed rack which is beveled or inclined as shown in Fig. 19. The pressure finger 47" is situated above and to the left of the pivot screw 38", so that, when the device 36" turns about said pivot screw, said pressure finger moves in an upwardly inclined arc. It is obvious that in thus moving, the 25 pressure finger will be guided by the inclined face of the part 61, which will force the pressure finger and with it the dog-rocker toward the back of the machine. It is also obvious that the parts will be held 30 against such motion as long as the pressure on the finger key is maintained, and that they will be free to move the instant such pressure is removed. The operation is similar in principle to that of the first form.

55 The rack 60 may or may not be pivotally connected with the carriage. If said rack is pivoted, any suitable means may be provided for locking said rack in its normal position to prevent it from being raised by 60 the pressure pin 47". The member 36 is in effect an angled lever having the holding dog 46 on one arm thereof and the pressure pin or finger 47 on another arm thereof. This lever is pivoted to the dog carrier on an 65 axis which is substantially parallel with the

direction of motion of said dog carrier and with the axis of the escapement wheel. It will be perceived that when the dog 46 is in engagement with the escapement wheel, the carriage is held against motion by the pressure members acting through this lever. 70

While I have shown and described several modifications of my invention, it will be understood that various other changes in the details of construction and arrangement may be made without departing from the gist 75 of my improvements.

What I claim as new and desire to secure by Letters Patent, is:—

1. In a typewriting machine, the combination with a carriage, of escapement mechanism comprising a rack; key-controlled dogs co-operating with said rack; and a pair of members one of which is pressed by the key into engagement with the other while the dog which is in engagement with the rack is maintained against lateral movement toward a tooth of said rack, said rack being held against motion by such pressure of one of said members against the other. 80

2. An escapement mechanism, comprising in combination a feed rack, a dog normally out of engagement with said rack, a pressure member connected with said dog, and a member having an inclined surface which is engaged by said pressure member when said dog is in engagement with said rack, the construction and arrangement being such that said pressure member comes into contact with said inclined surface at the end of 95 the motion of said dog into engagement with said rack. 100

3. An escapement mechanism comprising in combination a feed rack; a dog mounted for motion toward and from said feed rack and also mounted for motion with said feed rack, means for moving said dog at right angles to said rack to bring the dog into engagement with said rack; and means comprising an inclined surface for guiding said 110 dog away from said rack in an oblique path, such that as said dog moves away from said rack it also moves with said rack. 105

4. An escapement mechanism comprising in combination a feed rack provided with an 115 inclined surface; a dog co-operating with said feed rack; and a pressure member connected with said dog and adapted to be pressed against said inclined surface when a key is depressed. 120

5. An escapement mechanism comprising in combination a feed rack; a dog co-operating with said rack; means for moving said dog directly toward said rack; and a part having an inclined surface for guiding said 125 dog away from said rack in an oblique path. 130

6. In an escapement mechanism, the combination with an escapement rack and a dog carrier, of two dogs each movable with said dog carrier toward and from said rack and

- each movable relatively to said dog carrier in the direction of the feed of the rack; and means for momentarily holding one of said dogs against motion in the direction of feed 5 when said dog is in engagement with said rack, said means including a pressure member connected with said dog and a coöperating part having an inclined surface across which said pressure member is arranged to move.
7. An escapement mechanism comprising in combination an escapement wheel; a rotary part connected with said wheel and having a frusto-conical surface, a dog having a pressure member adapted to engage said frusto-conical surface; and means for moving said dog into and out of engagement with said escapement wheel.
8. An escapement mechanism comprising 20 in combination an escapement rack; a part mounted to move with said escapement rack, said part having an inclined surface; a dog having a pressure member adapted to engage said inclined surface; and means for moving said dog into and out of engagement with said rack.
9. An escapement mechanism comprising in combination an escapement rack; a dog carrier; a dog mounted on said dog carrier 30 with freedom of motion in the direction of feed of said feed rack; a pressure member connected with said dog; and a part adapted to be engaged by said pressure member at the end of the inovement of said dog into engagement with said rack and to guide said dog in its motion out of engagement with said rack to move in an oblique path.
10. In an escapement mechanism, the combination with the escapement rack; of a dog carrier; a stepping dog mounted on said dog carrier; a second dog mounted on said dog carrier with freedom of motion in the direction of feed of said rack; a pressure member connected to said second dog; and a part 45 adapted to be engaged by said pressure member to momentarily hold said second dog against motion in the direction of feed of said rack when said second dog is in engagement with said rack, and having an inclined surface for guiding the return motion of said second dog in an oblique path.
11. In a typewriting machine, the combination of a carriage; a rack bar mounted on said carriage; a rotary shaft geared to said 50 rack bar; an escapement wheel mounted on said shaft; a wheel having a frusto-conical surface rigidly mounted on said shaft; a key controlled dog carrier having a stepping dog mounted thereon; a second dog pivotally mounted on said dog carrier so as to be free to move with said escapement wheel; a pressure member connected with said second dog and adapted to engage said frusto-conical surface; and a returning spring for the said 55 second dog.
12. In a typewriting machine, the combination with a power driven carriage, of escapement mechanism comprising a rack, a dog carrier, means for moving said dog carrier in a direction substantially at right angles to the direction of feed of said rack, a holding dog pivotally mounted on said dog carrier and having its pivotal axis substantially parallel to the direction of motion of said dog carrier, a spring pressing said dog 70 in a direction the opposite of that in which the rack moves, and means for arresting and retaining said holding dog in rack-holding position until the depressed finger key is released.
13. In a typewriting machine, the combination with a power driven carriage and keys, of escapement mechanism comprising a feed rack, a dog carrier, a dog pivotally mounted on said dog carrier with its pivotal 75 axis substantially parallel with the direction of motion of said dog carrier, and means for guiding the motion of said dog away from said rack in an oblique path.
14. An escapement mechanism comprising 80 in combination a feed rack; a lever mounted for bodily motion toward and from said rack and having on one arm thereof a dog which coöperates with said rack and on another arm thereof a pressure device; and 85 means comprising an inclined surface which is engaged by said pressure device when said dog is in engagement with said rack, whereby said dog is guided away from said rack in an oblique path.
15. An escapement mechanism comprising 90 in combination a feed rack provided with an inclined surface; and a lever mounted for bodily motion toward and from said rack and having on one arm thereof a dog which 95 coöperates with said rack and on another arm thereof a pressure member adapted to be pressed against said inclined surface when a key is depressed.
16. In a typewriting machine, the combination of keys; a carriage, and escapement mechanism comprising a feed rack for said carriage; a key-controlled lever mounted for bodily motion toward and from said rack and for rocking motion in the direction of 100 feed of said rack; a dog on one arm of said lever; a pressure device on another arm of said lever; and a part having an inclined surface which is engaged by said pressure device when a key is depressed, whereby said 105 lever is momentarily held against rocking, and said inclined surface acting as a guide for said pressure device while the dog is moving out of engagement with the rack.
17. An escapement mechanism comprising 110 in combination an escapement wheel; a rotary part connected with said wheel and having a frusto-conical surface; a lever having on one arm thereof a dog which coöperates 115 with said escapement wheel and on the other 120
- 125
- 130

- a pressure device adapted to engage said frusto-conical surface; and means for moving said lever bodily toward and from said escapement wheel and said rotary part.
5. 18. In a typewriting machine, the combination with a power-driven carriage, of a feed-rack, two feed dogs adapted to coöperate with said rack, both of said dogs being spring pressed in a direction opposite to that in which said feed rack moves, and means including coöoperating pressure members, one of which is inclined for holding one of said dogs against motion with said feed rack when a key is depressed and for guiding said dog away from said rack in an oblique path.
10. 19. In a typewriting machine, the combination of a power driven carriage, a feed rack, two feed dogs adapted to coöperate with said feed rack, both of said feed dogs being spring pressed in a direction the opposite of that in which said feed rack moves, a pressure member connected with one of said dogs, and an inclined surface that is engaged by said pressure member when said dog is in engagement with said feed rack and that guides said pressure member away from said feed rack in an oblique path.
15. 20. In a typewriting machine, the combination of a power driven carriage, a feed rack, two feed dogs adapted to coöperate with said feed rack, both of said feed dogs being spring pressed in a direction the opposite of that in which said feed rack moves, two pressure members, one of which is mounted on one of said dogs and one of which is inclined, said pressure members coöperating when said dog is in engagement with the feed rack and guiding said dog in an oblique path as it moves out of engagement with said feed rack.
20. 21. In a typewriting machine, the combination with keys and a carriage, of escapement mechanism comprising a rack, a dog-rocker, a holding dog mounted on said dog-rocker and movable into and out of engagement with said rack; said holding dog being movable on said dog-rocker in the direction of feed movement of said rack, and two coöperating pressure members, one of which is connected with said holding dog and comes into contact with the other at the end of the motion of said holding dog into engagement with the rack, said pressure members preventing motion of said holding dog with said rack until the depressed key is released.
25. 22. In a typewriting machine, the combination with keys and a carriage, of escapement mechanism comprising a rack, a stepping dog, a holding dog mounted for motion into and out of engagement which the rack and also for motion with said rack, and two coöperating pressure members one of which is connected with said holding dog and the other of which is connected with said rack, said pressure members being pressed into engagement by force derived from a key and serving to prevent the holding dog from moving with the rack until the key is released.
30. 23. An escapement mechanism, comprising in combination a feed rack, a dog normally out of engagement with said rack and mounted for motion in two directions, a pressure member connected with said dog, and a member having an inclined surface which is engaged by said pressure member when said dog is in engagement with said rack, the construction and arrangement being such that said pressure member comes into contact with said inclined surface at the end of the motion of said dog into engagement with said rack.
35. 24. An escapement mechanism comprising in combination a feed rack provided with an inclined surface; a dog coöoperating with said feed rack and mounted for motion in two directions; and a pressure member connected with said dog and adapted to be pressed against said inclined surface when a key is depressed.
40. Signed at the borough of Manhattan, city of New York, in the county of New York, and State of New York, this 14th day of November A. D. 1904.
